(57) **CLAIM**

The ornamental design for a chair shell, as shown and described.

DESCRIPTION

FIG. 1 is a perspective view of a chair shell embodying the new design.

FIG. 2 is a left side view thereof, the right side view being a mirror image of the left side view.

FIG. 3 is a front elevational view thereof.

FIG. 4 is a rear elevational view thereof.

FIG. 5 is a top plan view thereof.

FIG. 6 is a bottom plan view thereof.

FIG. 7 is a perspective view of an alternative embodiment of the chair shell.

FIG. 8 is a left side view thereof, the right side view being a mirror image of the left side view.

FIG. 9 is a front elevational view thereof.

FIG. 10 is a rear elevational view thereof.

FIG. 11 is a top plan view thereof; and,

FIG. 12 is a bottom plan view thereof.
